UNITED STATES PATENT OFFICE.

HENRY T. CLEARY, OF ST. LOUIS, MISSOURI.

ELECTRICAL PERMUTATION-LOCK SYSTEM.

No. 893,902.

Specification of Letters Patent.

Patented July 21, 1908.

Application filed April 10, 1908. Serial No. 426,198.

To all whom it may concern:

Be it known that I, HENRY T. CLEARY, a citizen of the United States, and a resident of the city of St. Louis and State of Missouri, have invented a new and useful Improvement in Electrical Permutation-Lock Systems, of which the following is a specification.

My invention relates to electric permutation lock systems and has for its principal objects to provide for the easy changing of the combination; to secure simplicity of construction and cheapness in the installation of such a system; to provide for adapting a permutation lock system to any number of doors; and to secure other advantages hereinafter described and claimed.

It consists principally in the arrangement of parts hereinafter described and claimed.

In the accompanying drawings, which form part of this specification, and wherein like symbols refer to like parts wherever they occur, Figure 1 is a diagrammatic view of a system showing one embodiment of my invention having two locks in the system and having the circuit closers for the loops connecting the first and second switch points of the switches, those for the loops containing the locks and those for the loops containing the alarms, electrically actuated; Fig. 2 is a diagrammatic view of a system showing another embodiment of my invention in which said circuit closers are mechanically actuated; Fig. 3 is a diagrammatic view of the embodiment of my invention shown in Fig. 2, and having two locks in the system.

An electrically releasable lock 1 is mounted in position to lock the door N of a house, safe or other structure. Said lock 1 is electrically connected to a wire loop 2. Said loop 2 contains an electric battery 3 and a spring retracted armature 4 of an electromagnet 5. Mounted adjacent to the terminals of said loop are a plurality of three point switches a', b', c', d' . Two points 6, 7 of each of said switches are electrically connected through a loop 8, 9, 10, 11 containing a spring retracted circuit closer $a^2 b^2 c^2 d^2$. The third point 12 of the first switch a' and the backstop 13 of the first point 6 of said first switch a' are electrically connected to said first mentioned loop 2. The forestop 14 of each third switch point 12 is electrically connected to the backstop 15 of the second switch point 7 of the corresponding switch and to the backstop 13 of the first switch point 6 of the next suc-

cessive switch and to the third switch point 12 of said next successive switch. The forestop 14 of the third switch point 12 and the backstop 15 of the second switch point 7 of the last switch are electrically connected to the backstop 16 of the armature 4 contained in said first mentioned loop 2. The forestops 17, 18 of the first and second switch points 6, 7 of the several switches are electrically connected in multiple to a loop 19 containing an electric battery 20 and the electromagnet 5 arranged to actuate said armature 4. Having one of its terminals electrically connected to said first mentioned loop 2 and its other terminal electrically connected to the forestop 21 of said armature is a loop 22 containing an electrically actuated alarm y^3 . Said last mentioned loop 22 when closed by said armature 4 and the portion of said first mentioned loop 2 included between the terminals of said last mentioned loop 22 constitute a closed circuit containing said first mentioned electric battery 3.

Mounted in position to actuate respectively the circuit closers $a^2 b^2 c^2 d^2$ are a plurality of electromagnets 23, 24, 25, 26. Said electromagnets 23, 24, 25, 26 are electrically connected in multiple to a wire 27 common to a plurality of loops containing an electric battery 28. Electrically connected to each of said electromagnets 23, 24, 25, 26 is a second wire 29, 30, 31, 32. Said second wires 29, 30, 31, 32 when separately connected to said common wire 27 constitute as many separate loops as there are electromagnets 23, 24, 25, 26, all however containing a common electric battery 28. Said last mentioned loops extend to a point in the wall preferably near the door N. At this terminal point of said loops containing the wires 27, 29, 30, 31, 32, a series of push buttons Y extend through holes provided therefor in the wall. There are as many push buttons Y as there are switches $a' b' c' d'$ and one additional push button 33 for operating the restoring circuit hereinafter described. All of said push buttons Y are connected on their inner ends to the wire 27, common to said loops and are arranged to be brought by their manipulation into contact with the second wire 29, 30, 31, 32 of said loops respectively. On the outside faces of said push buttons Y are suitable letters or characters, for instance A B C D and the like. The restoring circuit push button 33 extends through a hole in said wall adjacent to said operating push button

Y. Having terminals at a point adjacent to said restoring circuit push button 33 is a restoring circuit 34. Said restoring circuit 34 contains an electric battery 35 and a plurality of electromagnets 36, 37, 38, 39. Said electromagnets are mounted in positions to open said circuit closers a^2 b^2 c^2 d^2 , respectively. Said restoring circuit 34 has additional terminals 40, 41 adjacent to the door 10 N. Mounted on said door N is a circuit closer 42 in position to be brought into contact with said additional terminals 40, 41 by the opening of said door N.

This embodiment of my invention can be applied to a plurality of locks without increasing the number of switches a' b' c' d' or the number of loops 8, 9, 10, 11 connecting the first and second switch points 6, 7 of said switches respectively. In this case there are 20 a plurality of loops 2 each electrically connected to one of said locks 1, and containing a spring retracted circuit closer X' Y' and all being electrically connected in multiple to said first mentioned electric battery 3 and 25 said first mentioned armature 4 and having common terminals.

Preferably there is an additional electric bell X^3 Y^3 for each additional lock, in which case, there are a plurality of alarm loops 22 30 each containing an electric bell X^3 Y^3 and a spring-retracted circuit closer X' Y' and all having in common the terminals and connections hereinbefore described for the single alarm loop. Each lock loop 2 and the corresponding alarm loop 22 have a circuit closer X' Y' in common which is preferably the armature of an electromagnet. Mounted in position to actuate said circuit closers X' Y' respectively are a plurality of electromagnets 40 43, 44. Said electromagnets 43, 44 are electrically connected in multiple to the wire 27 containing the battery 28 and having connected thereto in multiple the electromagnets 23, 24, 25, 26. Said electromagnets 45 43, 44 are respectively connected to the wires 45, 46. To each of said wires 45, 46 is connected a set of push buttons X, Y. There are as many sets of push buttons X, Y as there are locks. In this case each of the 50 second wires 29, 30, 31, 32 which are electrically connected to the electromagnets 23, 24, 25, 26, respectively, has as many terminals as there are sets of push buttons X, Y, and the arrangement of the respective sets of 55 terminals and push buttons X, Y with respect to each other is the same as that hereinbefore described for single sets of said terminals and push buttons. In this case the restoring circuit contains as many additional 60 electromagnets 47, 48 as there are additional locks. Said additional electromagnets are mounted in position to open the circuit closers X' Y' . The restoring circuit is also provided with additional terminals, an additional push button 33 and an additional circuit closer 42

for each additional lock. The arrangement of said additional push button 33 and said additional circuit closer 42 with respect to the additional terminals of the restoring circuit is the same as that above described for a single lock. 70

A modified form of the means for closing the loops 8, 9, 10, 11 is shown in Figs. 2 and 3.

In this case, said loops 8, 9, 10 extend through openings made for their passage in the wall and terminate in a cabinet 49 fixed to the outside of said wall. Said cabinet 49 is preferably at some point adjacent to the door. Each of said loops 8, 9, 10, is normally open at a point within said cabinet 49. 75 Adjacent to each of said openings is a pivotally mounted arm 50. Said arm 50 has an upwardly extending lug 51 thereon and is connected by a spring 52 to the wall of the cabinet 49. The tendency of said spring 52 80 is to bring said arm 50 into contact with the terminals of its corresponding loop 8, 9, 10. Adjacent to said arm 50 is a bell crank 53 having a lug 54 thereon. Said lug 54 normally bears against the lug 51 thereby holding the 85 arm 50 away from contact with the terminals of its corresponding loop 8, 9, 10. Mounted in the wall of said cabinet 49 adjacent to each of said bell cranks 53 and in position to bear against the outer arm thereof is a spring- 90 retracted push button. Said push buttons extend through holes provided therefor to the outside of the wall of said cabinet. Said push buttons are marked on their outer ends with suitable letters or characters. Mounted 95 in the wall of said cabinet in a position to bear against each of said arms 50 is a restoring pin. Said restoring pins 55 also extend through holes provided therefor to the outside of the wall of the cabinet 49. Obviously, this form of the means for closing the 100 loops 8, 9, 10 may be used when the system comprises a plurality of locks. In this case a branch lock loop 2, a cabinet 49, a set of loops 8, 9, 10 and the means for closing said 105 loops, and a branch restoring circuit and the restoring devices connected therewith are provided for each lock 1. Each of said branch lock loops 2 extends into the corresponding cabinet 49 and is normally open at 110 some point therein. The devices for closing and restoring said branch lock loops are the same as those above described for closing and restoring the loops 8, 9, 10. It is preferable in this case also to have an additional electric bell X^3 Y^3 for each additional lock. In order that each of said electric bells X^3 Y^3 115 may be connected only to the series of operating devices adjacent to its corresponding lock 1, a plurality of branch alarm loops 56 120 connect each of said electric bells X^3 Y^3 , to said operating devices respectively. Each of said branch alarm loops 56 is normally open at a point adjacent to the pivoted arm 50 of its corresponding operating device and 125 130

is arranged to be closed by the operation of said operating device and restored by the same restoring means.

The operation of my system is as follows:

- 5 In Fig. 1 two locks are shown connected to the system. Assuming the push buttons adjacent to each lock to be lettered alphabetically from *a* to *d* beginning on the left and the switches to be similarly lettered but 10 beginning on the right, the system is represented as set for the combination *b*, *d*, that is, the second and fourth switches *b'*, *d'* are set in contact with their respective back stops and all other switches are set in contact with their respective forestops. Suppose it is desired to open the door M. Pressing the push buttons *b* and *d* in the set X brings said push buttons into contact with the terminals of the respective loops, 9, 11, 20 with which they are arranged to coöperate. By this operation a closed circuit is established beginning at the battery 28 passing through the electromagnets 24, 26, the wires 30, 32, then through the wire 45, the 25 electromagnet 43, the wire 27 and back to the battery 28. Thereupon the electric current passing from the battery 28 energizes the electromagnets 24, 26, 43, whereby the armatures *b*² *b*² *x'* are brought into contact 30 with their respective backstops thereby closing the adjacent openings in the loops 9, 11, and in the branch lock loop electrically connected to the lock of the door at M and in the branch alarm loop containing the electric bell X³. By this operation a closed circuit is established beginning at the battery 3, passing through the armature 4 the second switch point 7 of the last switch *d'*, the loop 11, the first switch point 6 of the last switch 40 *d'*; the third switch point 12 of the last switch *d'*, the second switch point 7 of the second switch *b'*, the loop 9, the first switch point 6 of the second switch *b'*, the third switch point 12 of the first switch *a'*, the 45 branch lock loop containing the lock of the door at M, the said lock and back to the battery 28. Thereupon the current passing from the battery 3 actuates the lock of the door at M unlocking the same. In the 50 course of the movement of said door the circuit closer 42 thereon passes across the terminals 40, 41 of the restoring circuit 34 thereby establishing a closed circuit beginning at the battery 35, passing through the 55 wire extending therefrom to the terminal 40, through the circuit closer 47 and the terminal 41, thence back along the wire extending from the terminal 41, through all of the electromagnets in said restoring circuit 60 34 in succession and then back to the battery 35. Thereupon the current passing from said battery 35 energizes the electromagnets 37, 39, 43 in said restoring circuit 34 whereby the circuit closers *b*², *b*⁴, X' are restored 65 to their normal positions. Said restoring

circuit 34 may be closed and the other circuits restored thereby by pressing the restoring push button 33. Pressing any push button which is marked with a letter or character not in the combination selected, 70 rings one of the alarms and has no effect on the lock. For instance, pressing the push button *c* in the set X brings said push button into contact with the terminal of the loop 10 with which said push button *c* is arranged to coöperate, thereby establishing a closed circuit beginning at the battery 28 passing through the electromagnet 25, the wire 31, the wire 45, the electromagnet 43, and back to the battery 28. Thereupon the electric 75 current passing from the battery 28 energizes the electromagnets 25, 43 whereby the armatures *c*² X' are brought into contact with their respective backstops thereby closing the adjacent openings in the loop 10 80 and in the branch lock loop electrically connected to the lock of the door at M and the branch alarm loop containing the electric bell X³. By this operation a closed circuit is established beginning at the battery 20 90 passing through the electromagnet 5, the second switch point 7 of the third switch *c'*, the loop 10, the first switch point 6 of the third switch *c'* and back to the battery 20. Thereupon the current passing from the battery 20 95 energizes the electromagnet 5 whereby the armature 4 is brought into contact with its forestop. By this operation a closed circuit is established beginning at the battery 3, passing through the electric bell 100 X³, the branch loop 22, containing said bell, the circuit closer X', therein, and back to the battery 3. Thereupon the electric current passing from the battery 3 actuates the electric bell X³ ringing same. Since in the 105 course of this operation the lock loop 2 remains open, the lock remains locked.

In the arrangement of my system shown in Figs. 2 and 3, the switches are represented as being set for the combination *a*, *c*; that is, the first and third switches *a'* *c'* are set in contact with their respective backstops and the second switch *b'* is set in contact with its forestop. If there were more switches, all others would be set as the second *b'*. With the 115 switches so set pressing the first and third push buttons *a*, *c* moves their corresponding bell cranks 53 away from contact with the lugs 51 on the respective arms 50. Whereupon, the springs 52 move said arms into 120 contact with the adjacent terminals of the loops 8, 10. In this case, any one of the arms 50 can be restored to its normal position by pressing the corresponding restoring pin 55, whereupon the lug 54 on the appropriate bell 125 crank again engages the lug 51 on the arm 50. The rest of the operation of the system is substantially as described for the arrangement shown in Fig. 1. If more than one lock is connected to this arrangement of the 130

system as shown in Fig. 3, it will first be necessary to press the push button arranged to close the adjacent opening in the branch lock loop. In this case, pressing any of the push buttons *a*, *b*, *c* will close the adjacent opening in the corresponding branch of the alarm circuit. Otherwise, the operation is substantially the same as for a single door.

The system obviously admits of considerable modification without departing from my invention, and hence I do not wish to be limited to the specific construction hereinbefore described. For instance, instead of three or four operating devices as shown in the drawings, any number may be used. Also instead of two doors as shown in Figs. 2 and 3, any number of doors may be connected to a single system. The bell may be a permanent alarm or it may be arranged to cease whenever the operating device which started it is restored. Also, a single bell could be used for any number of doors. The alarm could be in the house, safe or other structure to which the system is attached, or at police headquarters, or elsewhere. The alarm could be a bell, whistle, annunciator or other device. Obviously, also, my system can be applied not only to doors, but also wherever locks are used; as, for instance, to the drawers of a desk. Obviously, also, the electric current instead of being supplied from batteries might come from any other source of electrical energy whether within or without the structure in which the system is installed. The electromagnets in the restoring circuit might be connected either in series or in multiple and arranged to restore the respective circuit closers to their normal positions either singly or simultaneously. Suppose the system is installed in a boarding house. No keys need be provided for the guests and yet any guest by simply knowing the combination can get into the house at any time. In order to provide against the acts of any departed guest whose honesty may be doubted, it is only necessary to change the combination. This statement would apply with equal force to former servants. In a hotel, if the system were connected to the locks of the guests' rooms, it would be desirable to have a different combination for each lock. In that case, a complete system like that shown in Fig. 2 would be provided for each room, the respective alarm systems being connected to an annunciator in the hotel office. Since pressure on any button, the letter or character of which is not a part of the combination selected, sounds the alarm, a burglar or anyone not knowing the combination, attempting to unlock the door would immediately betray his presence.

What I claim is:

1. An electric permutation lock system comprising a loop containing a source of elec-

trical energy, an electrically releasable lock, and the armature of an electromagnet, a second loop containing a source of electrical energy and an electromagnet arranged to coöperate with said armature and having a plurality of pairs of terminals, a plurality of loops each having a manually controlled circuit closer therein and terminating in a permutation switch, said switches being arranged to electrically connect in series any predetermined set of said last mentioned loops to said first mentioned loop and to electrically connect in multiple the remainder of said last mentioned loops to said second loop.

2. An electric permutation lock system comprising a loop containing a source of electrical energy, an electrically releasable lock and the armature of an electromagnet, a second loop containing a source of electrical energy and an electromagnet arranged to coöperate with said armature and having a plurality of pairs of terminals, a plurality of loops each having a manually controlled circuit closer therein and terminating in a permutation switch, said switches being arranged to electrically connect in series any predetermined set of said last mentioned loops to said first mentioned loop and to electrically connect in multiple the remainder of said last mentioned loops to said second loop, and another loop containing an electrically actuated alarm and having one of its terminals electrically connected to said first mentioned loop and its other terminal electrically connected to the forestop of said armature.

3. An electric permutation lock system comprising a loop containing a source of electrical energy, an electrically releasable lock and the armature of an electromagnet, a second loop containing a source of electrical energy and an electromagnet arranged to coöperate with said armature and having a plurality of pairs of terminals, a plurality of loops each having a manually controlled circuit closer therein and terminating in a permutation switch, said switches being arranged to electrically connect in series any predetermined set of said last mentioned loops to said first mentioned loop and to electrically connect in multiple the remainder of said last mentioned loops to said second loop, and means for restoring said system to its normal position, said restoring means comprising a normally open circuit containing a source of electrical energy, a plurality of electromagnets, and means for closing said circuit.

4. An electric permutation system comprising a loop containing a source of electrical energy, an electrically releasable lock, and the armature of an electromagnet, a second loop containing a source of electrical energy and an electromagnet arranged to coöperate with said armature and having a plurality of pairs of terminals, a plurality of loops each

having a manually controlled circuit closer therein and terminating in a permutation switch; said switches being arranged to electrically connect in series any predetermined set of said last mentioned loops to said first mentioned loop and to electrically connect in multiple the remainder of said last mentioned loops to said second loop, and means of restoring said system to its normal position, 10 said restoring means comprising a normally open circuit containing a source of electrical energy, a plurality of electro magnets, and means for closing said circuit, said closing means comprising an arm fastened to the 15 closure with which said system co-operates and arranged to be brought into contact with terminals of said circuit by the opening of said closure.

5. An electric permutation lock system 20 comprising a loop containing a source of electrical energy, an electrically releasable lock, and the armature of an electromagnet, a second loop containing a source of electrical energy and an electro magnet arranged 25 to co-operate with said armature and having a plurality of pairs of terminals, a plurality of loops each having a manually controlled circuit closer therein and terminating in a permutation switch, said switches being arranged 30 to electrically connect in series any predetermined set of said last mentioned loops to said first mentioned loop and to electrically connect in multiple the remainder of said last mentioned loops to said second loop, 35 each of said manually controlled circuit closers comprising the armature of an electro magnet and a loop containing a source of electrical energy, an electromagnet arranged to co-operate with said last mentioned armature and a normally open manually operable switch.

6. An electric permutation lock system 45 comprising a plurality of normally open loops having common terminals and containing a common source of electrical energy and a common armature of an electromagnet and each containing an electrically releasable lock and a manually controlled circuit closer, another loop containing a source of electrical 50 energy and an electromagnet arranged to co-operate with said armature and having a plurality of pairs of terminals, a plurality of loops each having a manually controlled circuit closer therein and terminating in a permutation switch, said switches being arranged 55 to electrically connect in series any predetermined set of said last mentioned loops to the common terminals of said first mentioned loops and to electrically connect 60 in multiple the remainder of said last mentioned loops to said second loop.

7. An electric permutation lock system 65 comprising a plurality of normally open loops having common terminals and con-

taining a common source of electrical energy and a common armature of an electromagnet and each containing an electrically releasable lock and a manually controlled circuit closer, another loop containing a source of electrical energy and an electromagnet arranged to co-operate with said armature and having a plurality of pairs of terminals, a plurality of loops each having a manually controlled circuit closer therein and terminating in a permutation switch, said switches being arranged to electrically connect in series any predetermined set of said last mentioned loops to the common terminals of said first mentioned loops and to electrically connect in multiple the remainder of said last mentioned loops to said second loop, and another plurality of normally open loops having common terminals all containing said first mentioned source of electrical energy and said armature and each containing an electrically actuated alarm and a manually controlled circuit closer.

8. An electric permutation lock system comprising a plurality of normally open loops having common terminals and containing a common source of electrical energy and a common armature of an electromagnet and each containing an electrically releasable lock and a manually controlled circuit closer, another loop containing a source of electrical energy and an electro-magnet arranged to co-operate with said armature and having a plurality of pairs of terminals, a plurality of loops each having a manually controlled circuit closer therein and terminating in a permutation switch, said switches being arranged to electrically connect in series any predetermined set of said last mentioned loops to the common terminals of said first mentioned loops and to electrically connect in multiple the remainder of said last mentioned loops to said second loop, each of said manually controlled circuit closers comprising the armature of an electromagnet and a loop containing a source of electrical energy, an electromagnet arranged to co-operate with said last mentioned armature and a normally open manually operable switch.

9. An electric permutation lock system comprising a plurality of three point switches, two points of each switch being electrically connected through a normally open loop containing a circuit closer, the third point of the first switch and the backstop of the first point of the first switch being electrically connected to a loop containing an electrically releasable lock, a source of electrical energy and the armature of an electromagnet, said armature being normally electrically connected to the forestop of one point of the last switch and to the backstop of another point of said last switch, the forestop of each third switch point being electrically connected to

- the backstop of the second switch point of the corresponding switch and to the backstop of the first switch point of the next successive switch and to the third switch point of said 5 next successive switch, the forestops of the first and second switch points of the several switches being electrically connected in multiple to a loop containing a source of electrical energy and an electromagnet arranged 10 to actuate said armature, and means for operating individually said first mentioned circuit closers.
10. An electric permutation lock system comprising a plurality of three point switches, 15 two points of each switch being electrically connected through a normally open loop containing a circuit closer, the third point of the first switch and the backstop of the first point of the first switch being electrically connected to a loop containing an electrically 20 releasable lock, a source of electrical energy and the armature of an electromagnet, said armature being normally electrically connected to the forestop of one point of the last switch and to the backstop of another point 25 of said last switch, the forestop of each third switch point being electrically connected to the backstop of the second switch point of the corresponding switch and to the backstop 30 of the first switch point of the next successive switch and to the third switch point of said next successive switch, the forestops of the first and second switch points of the several switches being electrically connected in multiple to a loop containing a source of electrical 35 energy and an electromagnet arranged to actuate said armature, and means for operating individually said first-mentioned circuit closers, said operating means comprising 40 a plurality of circuits each containing a source of electrical energy, an electromagnet and a normally open manually operable switch.
11. An electric permutation lock system comprising a plurality of three point switches, 45 two points of each switch being electrically connected through a normally open loop containing a circuit closer, the third point of the first switch and the backstop of the first point of the first switch being electrically connected to a loop containing an electrically 50 releasable lock, a source of electrical energy and the armature of an electromagnet, said armature being normally electrically connected to the forestop of one point of the last switch and to the backstop of another point 55 of said last switch, the forestop of each third switch point being electrically connected to the backstop of the second switch point of the corresponding switch and to the backstop 60 of the first switch point of the next successive switch and to the third switch point of said next successive switch, the forestops of the first and second switch points of the several switches being electrically connected

65 nected in multiple to a loop containing a source of electrical energy and an electromagnet arranged to actuate said armature, means for operating individually said first mentioned circuit closers, and means for restoring the system to its normal position. 70

12. An electric permutation lock system comprising a plurality of three point switches, two points of each switch being electrically connected through a normally open loop containing a circuit closer, the third point of the first switch and the backstop of the first point of the first switch being electrically connected to a loop containing an electrically releasable lock, a source of electrical energy and the armature of an electromagnet, said 80 armature being normally electrically connected to the forestop of one point of the last switch and to the backstop of another point of said last switch, the forestop of each third switch point being electrically connected to 85 the backstop of the second switch point of the corresponding switch and to the backstop of the first switch point of the next successive switch and to the third switch point of said next successive switch, the forestops of the first and second switch points of the several 90 switches being electrically connected in multiple to a loop containing a source of electrical energy and an electromagnet arranged to actuate said armature, means for operating individually said first-mentioned circuit closers, and means for restoring the system to its normal position, said restoring means comprising a normally open circuit containing 95 a source of electrical energy, a plurality of electromagnets, and the armatures of said magnets, and means for closing said last mentioned circuit.

13. An electric permutation lock system comprising a plurality of three point switches, 105 two points of each switch being electrically connected through a normally open loop containing a circuit closer, the third point of the first switch and the backstop of the first point of the first switch being electrically connected to a loop containing an electrically 110 releasable lock, a source of electrical energy and the armature of an electromagnet, said armature being normally electrically connected to the forestop of one point of the last switch and to the backstop of another point of said last switch, the forestop of each third switch point being electrically connected to 115 the backstop of the second switch point of the corresponding switch and to the backstop of the first switch point of the next successive switch and to the third switch point of said next successive switch, the forestops of the first and second switch points of the several 120 switches being electrically connected in multiple to a loop containing a source of electrical energy and an electromagnet arranged to actuate said armature, means for

operating individually said first mentioned circuit closers, and means for restoring the system to its normal position, said restoring means comprising a normally open circuit 5 containing a source of electrical energy, a plurality of electromagnets, and the armatures of said magnets, and means for closing said last mentioned circuit, said closing means comprising an arm fastened to the 10 closure with which said system coöperates and arranged to be moved across the terminals of said last mentioned circuit by the opening of said closure.

14. An electric permutation lock system 15 comprising a plurality of three point switches, two points of each switch being electrically connected through a normally open loop containing a circuit closer, the backstop of the first point of the first switch and the third 20 point of the first switch being electrically connected to a loop containing an electrically releasable lock, a source of electrical energy, and the armature of an electromagnet, said armature being normally electrically 25 connected to the forestop of one point of the last switch and to the back stop of another point of said last switch, the forestop of each third switch point being electrically connected to the backstop of the second switch 30 point of the corresponding switch and to the backstop of the first switch point of the next successive switch and to the third switch point of said next successive switch, the forestop of the first and second switch points 35 of the several switches being electrically connected in multiple to a loop containing a source of electrical energy and an electromagnet arranged to actuate said armature, and the forestop of said armature being electrically 40 connected through an electrically actuated alarm to said first mentioned source of electrical energy and means for operating individually said first mentioned circuit closers.

15. An electric permutation lock system 45 comprising a plurality of three point switches, two points of each switch being electrically connected through a normally open loop containing a circuit closer, the backstop of the first point of the first switch and the third 50 point of the first switch being electrically connected to a plurality of normally open loops, each containing a circuit closer, a source of electrical energy, an electrically releasable lock and the armature of an electromagnet, said armature being normally electrically 55 connected to the forestop of one point of the last switch and to the backstop of another point of said last switch, the forestop of each third switch point being electrically 60 connected to the backstop of the second switch point of the corresponding switch and to the backstop of the first switch point of the next successive switch and to the third switch point of said next successive

switch, the forestops of the first and second 65 switch points of the several switches being electrically connected in multiple to a loop containing a source of electrical energy and an electromagnet arranged to actuate said armature, and means for operating individually 70 said first mentioned and said second mentioned circuit closers.

16. An electric permutation lock system comprising a plurality of three point switches, two points of each switch being electrically 75 connected through a normally open loop containing a circuit closer, the backstop of the first point of the first switch and the third point of the first switch being electrically connected to a plurality of normally open 80 loops, each containing a circuit closer, a source of electrical energy, an electrically releasable lock, and the armature of an electromagnet, said armature being normally electrically connected to the forestop of one 85 point of the last switch and to the backstop of another point of said last switch, the forestop of each third switch point being electrically connected to the backstop of the second switch point of the corresponding switch 90 and to the backstop of the first switch point of the next successive switch and to the third switch point of said next successive switch, the forestops of the first and second switch points of the several switches being electrically 95 connected in multiple to a loop containing a source of electrical energy and an electromagnet arranged to actuate said armature, and means for operating individually 100 said first mentioned and said second mentioned circuit closers, said operating means comprising a plurality of circuits each containing a source of electrical energy, an electromagnet and a normally open manually operable switch.

17. An electric permutation lock system comprising a plurality of three point switches, two points of each switch being electrically connected through a normally open loop containing a circuit closer, the third point of the 110 first switch being electrically connected to a plurality of normally open loops each containing a circuit closer, a source of electrical energy, an electrically releasable lock, and the armature of an electro-magnet, said armature being normally electrically connected to the forestop of one point of the last switch and to the backstop of another point of said last switch, the forestop of each third switch point being electrically connected to the back 115 stop of the second switch point of the corresponding switch and to the back stop of the first switch point of the next successive switch and to the third switch point of said next successive switch, the forestops of the first and second switch points of the several switches being electrically connected in multiple to a loop containing a source of elec- 120 125

trical energy and an electromagnet arranged to actuate said armature, and the forestop of said armature being electrically connected to a plurality of normally open loops each containing said first mentioned source of electrical energy, a normally open circuit closer and an electrically actuated alarm, and means for operating individually said first

mentioned, said second mentioned, and said last mentioned circuit closers. ¹⁰

Signed at St. Louis, Missouri, this 4th day of April, 1908.

HENRY T. CLEARY.
